sham, Huntington Park, Calif.

Application September 19, 1934, Serial No. 744,690

6 Claims. (Cl. 24—263)

This invention has to do with well drilling equipment and has particular reference to slips for use in the rotary table of a well drilling rig. A general object of the invention is to provide simple, practical and improved slips for supporting tubing or pipe extending through a rotary table.

Another object of the invention is to provide effective slips each comprising two slip sections connected so that they may be handled as a single unit.

Another object of the invention is to provide slips each comprising a plurality of relatively movable sections assembled and related so that they may properly bear and seat in the bushing of a rotary table and conform to and effectively engage a pipe or tubing extending through the table.

Another object of the invention is to provide slips each comprising more than one slip section and connections between the sections which allow them to move toward and away from one another but which effectively prevent twisting, racking and relative longitudinal movement of the sections.

Another object of the invention is to provide slips of the character mentioned in which each of the connected slip sections carries a readily replaceable liner for engaging the pipe or tubing.

Another object of the invention is to provide slips embodying simple, inexpensive means for dependably holding replaceable liners against movement and displacement.

Another object of the invention is to provide slips of the character mentioned that are light in weight and easy to handle.

A further object of the invention is to provide slips of the character mentioned that embody improved handles.

The various objects and features of the present invention will be fully understood from a detailed description of a typical preferred form and application of the invention, throughout which description reference may be had to the accompanying drawings, in which:

Fig. 1 is a top or plan view of a portion of a rotary table illustrating the slips of the present invention arranged in the master bushing of the table. Fig. 2 is an enlarged central longitudinal detailed sectional view of one of the slips removed from the table. Fig. 3 is an elevation of the outer side of one of the slips. Fig. 4 is an enlarged, transverse detailed sectional view taken as indicated by line 4—4 on Fig. 3. Fig. 5 is an elevation of the inner side of one of the slips,

Fig. 6 is an enlarged, fragmentary, transverse detailed sectional view taken as indicated by line 6—6 on Fig. 3, and Fig. 7 is an edge or side elevation of the handle of one of the slips showing it in the upright position. 5

The slips of the present invention are adapted to be arranged in the bushing of the rotary table of a well drilling rig to support a drill pipe or the like. In Fig. 1 of the drawings we have illustrated a typical rotary table T carrying a master 10 bushing B. A set of slips S of the character provided by the present invention are arranged in the bushing B to engage and support a pipe P extending through the rotary table. While the slips S may be used in sets of three or more it 15 has been found desirable and advantageous to construct the slips of the present invention for use in pairs or sets of two. The sectional construction of the slips and their relatively light weight make it possible to use them in sets of 20 two in situations where it has previously been necessary to employ slips in sets of three or more. The above advantage of the invention will become apparent from the following description. The slips S may be alike or identical and we will 25 proceed with a detailed description of one slip S, it being understood that the description applies to the other slip.

The slip S of this invention includes, generally, two sections 10, means 11 connecting the sections 30 10 for limited play or relative movement, and replaceable liners 12 on the sections 10 for engaging the pipe P.

The connected sections 10 are adapted to be arranged or assembled in the opening of the 35 bushing B to engage the pipe P. The two sections 10 of the slip are alike or similar in shape and are complementary to make up or comprise the body of the slip. The inner sides or surfaces of the sections 10 are concave and cylindrically 40 curved to carry the replaceable liners 12 as will be hereinafter described. The major portions 13 of the exteriors of the sections 10 are tapered downwardly and inwardly and are transversely curved to properly bear in the tapered opening 45 of the bushing B. The outer or exterior surfaces 14 which extend upwardly from the major outer surfaces 13 to the tops of the sections may be inclined upwardly and inwardly as clearly illustrated in Fig. 2 of the drawings. The lower outer 50 or exterior surfaces 15 of the sections 10 may be inclined downwardly and inwardly at an increased angle.

The outer longitudinal sides or ends 16 of the sections 10 are preferably flat and vertical. When 55

the slips are in their operative positions in the bushing B the outer ends 16 of the sections 10 are substantially tangential to a relatively small circle concentric with the longitudinal axis of the bushing. The slips S are proportioned and related so that their adjacent opposing ends 16 are in spaced parallel relationship when the slips are in use. In practice large portions of the outer ends 16 may be bevelled away as at 17 to materially lighten the construction. In accordance with the invention the sections 10 are internally relieved or hollow, being provided with chambers or spaces 18. Because of the provision of the spaces 18 each of the bodies 10 consists of an inner wall 19 and an outer wall 20 connected by a central longitudinal web 21. Upper walls 22 and lower end portions 23 also operate to connect the inner and outer walls 19 and 20. Vertically or longitudinally spaced ribs 24 are provided at opposite sides of each web 21 and extend between the inner and outer walls 19 and 20. The webs 21 and the ribs 24 reinforce the hollow sections 10 and give them the necessary strength and rigidity. The sections 10 in being internally relieved or hollow as just described are light in weight so that the slip S is easy and convenient to handle.

The opposing longitudinal inner edges or ends 25 of the inner walls 19 are parallel and normally in spaced relation. The inner or opposing ends 25 may be substantially tangential to a relatively small circle concentric with the longitudinal axis of the bushing B. The opposing inner longitudinal edges or ends 26 of the outer walls 20 may be vertical but are cut back so that an opening or space of substantial width exists between them. The inner chambers or spaces 18 of course join the space between the ends 26. The extreme lower end portions 23 of the sections 10 may be solid except for spaced recesses 27. The tops or upper ends 28 of the sections 10 are preferably flat and horizontal.

The means 11 connects the two sections 10 of the slip so that they may be readily handled as a single unit and is such that the sections 10 may work or move toward and away from one another during use. The means 11 includes an elongate longitudinally extending lug or rib 29 on each section 10. The ribs 29 project outwardly from the inner walls 19 and are in spaced parallel relation with the inner ends 25. In practice the ribs 29 are integral with the sections 10 and are of substantial length. In the particular construction illustrated in the drawings the ribs 29 extend downwardly from the upper ends 28 of the sections 10. The means 11 includes connecting members in the form of pins or stud bolts 30 extending through horizontally aligned openings 31 in the ribs 29. There are at least two bolts 30 provided to connect the sections 10. Nuts 32 are threaded on the opposite end portions of the bolts 30 to limit the relative movement between the sections 10. Keys 33 may lock the nuts 32 against displacement. The bolts 30 are shiftable or slideable in the openings 31 and the parts are related and proportioned so that the sections 10 may have the desired relative horizontal play or movement. In accordance with the invention coiled springs 34 are arranged on the bolts 30 between the ribs 29 to yieldingly resist movement of the sections toward one another. The springs 34 may normally be under compression to exert outward forces on the sections 10. It will be apparent how the bolts 30 slidably fitting the longitudinally spaced pairs of openings 31 prevent racking and

twisting of the sections 10 and hold the sections against relative lateral and longitudinal movement. The springs 34 yieldingly resist the movement of the sections 10 toward one another and may aid in freeing the slips from the pipe P when the pipe is elevated.

The invention includes an improved handle for facilitating the carrying and handling of the slip S. The handle includes a shank 35 extending downwardly between the upper end portions of 10 the ribs 29. A pin 36 extends through openings 31 in the ribs 29 and an opening 37 in the shank 35 to pivotally connect the handle with the slip. Nuts 38 may be threaded on the pin 36 and may be locked against displacement by keys 39. Sufficient clearance is provided between the shank 35 and the ribs 29 to allow for the desired relative movement between the sections 10. The pin 36 aids the bolts 30 in connecting the sections 10 and in preventing twisting and other undesirable relative movement of the sections.

The major portion of the handle of the slip is substantially triangular in plan elevation as will be evident from an inspection of Fig. 1 of the drawings. The handle includes two branches or arms 40 diverging from the shank 35 and a transverse member or portion 41 joining the outer ends of the arms 40. Braces or supports 42 extend between and connect the portion 41 and the arms 40. The supports 42 may be in planes substantially normal to the longitudinal axis of the portion 41. In accordance with the invention the supports 42 are curved or bowed downwardly to engage the table T to hold the handle elevated from the table so that it may be readily engaged when it is in its lowermost position. The handle just described is proportioned so that it cannot pass downwardly through the opening in the bushing B in the event that the slip S falls through the opening. The greatest or outermost dimension of the handle is greater than the diameter of the opening in the bushing B so that the handle cannot pass through the opening in the bushing.

The liners 12 are arranged on the inner sides of the sections 10 to engage the pipe P. The liners 12 are the wear receiving elements of the slip and are preferably hardened. In the preferred form of the invention there is one liner 12 provided on each section 10 to cover the major portion of its inner side. Channels extend horizontally or circumferentially across the inner sides of the sections 10 and their upper and lower walls form shoulders 44 and 45. The shoulders 44 and 45 are undercut, that is, the shoulder 44 is inclined upwardly and outwardly and the shoulder 45 is inclined downwardly and outwardly. The shoulders 44 and 45 preferably extend between the opposite ends 16 and 25 of the sections 10. The liners 12 are adapted to be introduced or passed inwardly between the shoulders 44 and 45 from the outer or free ends 16. The upper and lower ends 46 of the liners 12 are pitched or inclined to cooperate with the shoulders 44 and 45 and lock the liners against inward detachment from the sections 10. The liners 12 bear against the inner sides of the sections 10 and the contacting surfaces of the liners and sections 10 are preferably concentrically curved about the central longitudinal axis of the bushing B. The opposite longitudinal edges 47 of the liners 12 may be flush with the opposite ends 16 and 25 of the body sections. Gripping parts or teeth 48 are provided on the liners 12 to engage and grip the pipe P. The teeth 48 extend circumferentially or horizontally and present upwardly facing edges for 75

biting into the pipe P when the pipe is supported by the slips.

The invention provides novel and effective means for removably retaining or locking the liners 12 in position on the sections 10. The liner retaining means includes partially circular notches 49 in the opposite ends of each liner 12. Horizontal openings 50 extend through the upper portions 22 and similar horizontal openings 51 extend through the lower portions 23 of the sections 10. The openings 50 and 51 are in alignment or register with the notches 49 and have counter bores 52 in their inner ends. The counter bores 52 extend through the shoulders 44 and 45 and oppose or directly communicate with the notches 49. Removable lock pins 53 are arranged in the openings 50 and 51 and are provided with heads 54. The heads 54 of the lock pins seat in the counter bores 52 and cooperate with the notches 49 to hold the liners 12 against detachment from the sections 10. Screws or keys 55 may be passed through openings in the pins 53 to retain the pins in position. The heads 54 of the lock pins cooperating with the notches 49 prevent lateral or horizontal movement of the liners 12 in both directions while the shoulders 44 and 45 hold the liners against longitudinal and inward movement.

It is believed that the utility and practicability of the slips provided by the present invention will be readily apparent from the foregoing detailed descriptions. The sections 10 of the slips S are internally relieved and are cut away at their opposite ends to be light in weight so that the slips may be easily and conveniently handled. The handles are shaped and constructed to facilitate the carrying and manipulating of the slips and are proportioned so that they cannot pass downwardly through the opening in the bushing B and thus prevent the slips from falling into the well. The supports 42 are adapted to engage the bushing or table T to hold the handle portions 41 spaced above the tables for convenient engagement. As there are only two slips S embodied in the set they may be quickly arranged in the bushing B about the pipe P. The slips S operate to support the pipe P in the bushing B in the well known manner. The liners 12 may be readily and quickly replaced when worn. To remove a liner 12 for replacement, the keys 55 are disengaged from the lock pins 53 and the lock pins are withdrawn from the openings 50 and 51. Following the withdrawal of the lock pins 53 the liners 12 may be readily withdrawn from the free or outer ends 16 of the sections 10. It is believed that it will be apparent how the new or replacement liners 12 may be introduced or passed between the shoulders 44 and 45 from the outer or free end 16 of the body sections 10 and secured in position by the pins 53.

The means 11 connecting the sections 10 of the slips allows limited horizontal play or movement between the sections. Because of their ability, to shift or move relative to one another the sections 10 may properly seat in the bushing B and cooperate with the pipe P. The spaced bolts 30 and the pin 36 prevent twisting or undesirable relative movement between the sections 10. The springs 34 operate to prevent undesirable move-

ment between the sections 10 when the slips are being carried or handled and may act to free or release the slips from the pipe P and the opening in the bushing B when the pipe is raised. The nuts 32 and 38 may be easily removed from the bolts 30 and pin 36 when it becomes desirable or necessary to disconnect the sections 10.

Having described only a typical preferred form and application of our invention, we do not wish to be limited or restricted to the specific form and application herein set forth, but wish to reserve to ourselves any modifications or variations that may appear to those skilled in the art or fall within the scope of the following claims.

Having described our invention, we claim:

1. A slip of the character described including a body section having spaced opposed undercut shoulders, a removable liner inserted between the shoulders, the ends of the liner being beveled to cooperate with the shoulders, there being notches in the ends of the liner, and lock pins removably connected with the body section and cooperating with the notches.

2. A slip of the character described including a body section having spaced opposed undercut shoulders, a removable liner inserted between the shoulders, the ends of the liner being beveled to cooperate with the shoulders, there being notches in the ends of the liner, and openings in the section at the shoulders, pins in the openings cooperating with the notches, and means removably locking the pins in place.

3. A slip of the character described including a body section having spaced opposed undercut shoulders, a removable liner inserted between the shoulders, the ends of the liner being beveled to cooperate with the shoulders, there being notches in both ends of the liner, and openings in the section at the shoulders, removable pins 40 in the openings, heads on the pins cooperating with the notches, and means locking the pins in place.

4. In apparatus of the character described, a slip, and a handle for the slip comprising a shank 45 connected with the slip, arms diverging outwardly from the shank, a transverse portion extending between and connecting the arms to form a substantially triangular handle structure, and a downwardly projecting member on said structure adapted to engage a support to space the said structure from the support for ready engagement by the user.

5. In apparatus of the character described a slip, and a handle for the slip comprising a shank 55 connected with the slip, arms diverging outwardly from the shank, a transverse portion connecting the outer ends of the arms, and braces extending between the arms and said portion and projecting downwardly to space the handle from a support.

6. In apparatus of the character described a slip, and a handle for the slip comprising a shank connected with the slip, arms diverging outwardly from the shank, and a transverse portion connecting the arms to provide a substantially triangular handle structure, said handle structure being of greater width than the slip.

ERWIN BURNS.
HARRY P. WICKERSHAM.
